(57) **CLAIM**

The ornamental design for a crib, as shown and described.

DESCRIPTION

FIG. 1 is a top, rear, left side perspective view of a crib showing our new design;

FIG. 2 is a bottom, front, right side perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a top, rear, left side perspective view showing the feet in an alternate position;

FIG. 10 is a bottom, front, right side perspective view thereof; and,

FIG. 11 is an exploded perspective view of the design shown in FIG. 2.

The broken lines in the drawings depict portions of the crib that form no part of the claimed design.

1 Claim, 11 Drawing Sheets
